UNITED STATES PATENT OFFICE

FELIX KAHN, OF SAN FRANCISCO, CALIFORNIA

HANGER FOR FORMS ON STEEL-BEAM CONSTRUCTION

Application filed October 10, 1928. Serial No. 311,588.

My invention relates to the fire-proofing of steel beams in building construction, and more particularly to means for attaching the form for the concrete fire-proofing to the steel beam.

It is customary in the art to suspend the form into which the concrete fire-proofing is poured from the steel beam by means of wires which are hooked over the top of the beam 10 and passed through the bottom of the form and twisted. This work is necessarily done by hand and requires a great deal of time and labor.

The principal object of my invention is to provide means by which the form can be attached to the beam quickly and easily. A second object is to provide a hanger for the described purpose which is readily adjustable to beams of different width. Other objects 20 and advantages of the invention will become apparent from the following specification which should be read with the understanding that the form, construction and arrangement of the several parts may be varied within the 25 scope of the claims hereto appended without departing from the spirit of the invention as expressed therein.

A preferred embodiment of my invention will now be described with reference to the 30 accompanying drawings, wherein:

Fig. 1 is a transverse section showing a form suspended from a steel beam by means of my hanger.

Fig. 2 is a plan view of the hanger.

Figs. 3 and 4 are sectional details taken on the respective lines 3—3 and 4—4 of Fig. 2.

Fig. 5 is a detail of a longer hook used for attaching the hanger to wider beams.

In the drawings, the reference numeral 1 40 designates a steel beam of I section as commonly used in building construction. The form, which is attached to said beam and into which the concrete fire-proofing is poured, is shown as comprising the usual bottom board 2, side boards 3, and transverse supporting pieces, one of which is shown at 4.

My invention resides in the hanger now to be described for suspending the said form from the beam 1.

A flat strip 5 of suitable metal, such as iron,

or soft steel, is provided at one end with an upwardly turned hook 6 adapted to engage one edge of the bottom flange of the beam 1. The end portions of the strip 5 are adapted to bear against the bottom of said beam, and its 55 central portion is bent downwardly, as shown at 7 in Fig. 1, to provide a space between it and the beam. The strip 5 is slotted for the greater portion of its length, the slot shown at 8 in Fig. 2 extending from the region of 60 the hook 6 to the opposite end of the strip. At said opposite end, one of the legs of the strip is bent downwardly and inwardly to form a hook 9, Fig. 1, and the end of the other leg is bent downwardly to form a spacing leg 65 10. At the end of the strip having the upwardly turned hook 6, a similar downwardly bent spacing leg 11 is formed, preferably by bending downwardly a portion of the material cut out in forming the slot 8. The legs 70 10 and 11 are adapted to bear against the bottom 2 of the form in order to properly space it from the bottom of the beam 1, as shown in Fig. 1.

The strip 5, described above, is secured to the form by means of a bolt 12 passing through the support 4 and the bottom of the form 2, and extending through the slot 8 in said stop. A nut 13 is screwed upon the upper end of the bolt 12, and its lower end 75 may conveniently be provided with a wing or handle 14. The hanger is attached to the beam 1 by the hooked end 6 at one side and by an S-shaped removable hook 15, Figs. 1, 2 and 4, at the other side. The removable hook 15 lies within the slot 8 of the strip 5 80 with its upwardly bent end engaging the edge of the beam 1 and its downwardly bent end lying opposite to the downwardly bent hook 9 of said strip, as shown in Fig. 1. A 90 wedge 16 is then driven between said oppositely disposed hooks thereby locking the strip 5, the hook 15, and the bottom flange of the beam 1 together.

The strip 5 can be attached to wider beams by providing longer removable hooks, as shown at 15' in Fig. 5. Therefore one size of strip can be used upon a number of different widths of beams merely by providing extra removable hooks of the proper length, 100

thus facilitating manufacture and reducing the stocks.

In using the device, the requisite number of strips 5 are first attached to the form at the place where the latter is made up. The form with the strips secured thereto is then placed in position around the beam 1 and secured to it by the removable hooks 15 and the wedges 16. After the concrete has been 10 poured and has set, the form is removed by unscrewing the bolts 12, leaving the strips 5, hooks 15, and wedges 16 embedded in the concrete.

It will be apparent to those skilled in the art that my hanger enables a form to be secured in position upon a beam with considerably less labor than is commonly necessary when the usual type of wire hanger is used. Moreover, all the parts of my device except the bolt 12, which is recovered, and the nut 13, can be manufactured cheaply and in quantities by stamping from sheet metal, so that the cost of the materials used is no greater than the cost of the wire used in the ordinary method of hanging. My device also insures accurate spacing of the form with relation to the beam, such spacing being determined by the legs 10 and 11 and the lateral position of the hanger in the form, and since 20 the hanger is secured to the form while the latter is on the floor or work-bench, the lateral positioning of said hanger is easily and accurately accomplished.

I claim:

35 1. A device for hanging forms from beams comprising a slotted member having means at one end to engage one side of the beam; a connecting member adapted to lie within said slot and to engage the other side of the beam; means for connecting said members together to clamp them upon the beam; and means for removably securing said slotted member to the form.

45 2. A device for hanging forms from beams comprising a slotted member having means at one end to engage one side of the beam; a connecting member adapted to lie within said slot and to engage the other side of the beam; means for connecting said members together to clamp them upon the beam; and a bolt extending through the bottom of the form and through said slot for removably securing said slotted member to said form.

55 3. A device for hanging forms from beams comprising a member having a hook at one end and a longitudinal slot at the other end, one leg of said slotted end being bent downwardly to form a spacing lug abutting against the form; a second spacing lug depending from the hooked end of said member; a second hooked member lying within said slot; means for connecting said members together to clamp their hooks upon the beam; and means for removably securing the form to said slotted member.

4. A device for hanging forms from beams comprising a member having means at one end for engaging one side of the beam and a longitudinal slot at the other end, one leg of said slotted end being bent downwardly 70 to form a hook; a connecting member having means for engaging the other side of the beam, said connecting member lying within said slot and having a downwardly directed hook opposite to the hook of said slotted member; a wedge adapted to be driven between said hooks to clamp said members upon the beam; and means for removably securing one of said members to the form.

5. A device for hanging forms from beams 80 comprising a pair of over-lapping members, each having an upwardly turned hook at one end adapted to engage opposite sides of the beam and a downwardly and oppositely turned hook at the other end; a wedge adapted to be driven between downwardly turned hooks to clamp said members upon the beam; and means for removably securing one of said members to the form.

6. A device for hanging forms from beams 90 comprising a member having an upwardly turned hook at one end, a downwardly turned hook at the other end, and a downwardly turned spacing lug in the region of each end; a connecting member having an upwardly turned hook at one end and a downwardly turned hook at the other end; a wedge adapted to be driven between said downwardly turned hooks to clamp said upwardly turned hooks upon the beam; and means 100 for removably securing a form to the first mentioned member in contact with its spacing lugs.

In testimony whereof I have signed my name to this specification.

FELIX KAHN.
